UNITED STATES PATENT OFFICE

WILLIAM EDWARD SCOFIELD, OF AUGUSTA, GEORGIA, ASSIGNOR OF TWO-THIRDS TO LUTHER PURCELL POWELL AND JACOB WILSON THORNE, OF SAME PLACE.

ACETYLENE-GAS GENERATOR.

SPECIFICATION forming part of Letters Patent No. 657,364, dated September 4, 1900.

Application filed May 22, 1899. Serial No. 717,796. (No model.)

To all whom it may concern:

Be it known that I, WILLIAM EDWARD SCOFIELD, a citizen of the United States, residing at Augusta, in the county of Richmond and 5 State of Georgia, have invented certain new and useful Improvements in Acetylene-Gas Generators; and I do hereby declare the following to be a full, clear, and exact description of the invention, such as will enable others skilled in the art to which it appertains 10 to make and use the same.

This invention relates to those acetylene-gas generators having a plurality of carbide charges adapted to be introduced successively into the water of the generating-tank.

My objects are the provision of a generating-tank of novel construction into which the carbide charges or cartridges can be introduced without causing a mixture of air with 15 the gas and insuring against escape of the gas being generated and novel means for holding the cartridges in position for submerging and for releasing them successively and guiding and maintaining them when sub- 20 merged.

The invention comprises certain improved features of construction and novel combinations and adaptations of parts fully set forth hereinafter, and particularly recited in the 25 appended claims.

In the accompanying drawings, Figure 1 is a side elevation of my gas-generator complete. Fig. 2 is an end elevation of the generating-tank and frame for supporting the 30 carbide-cartridges. Fig. 3 is an elevation, partly in section, of the gasometer and its connections. Fig. 4 is a horizontal section of same, taken on the line 4-4 of Fig. 3. Figs. 5 and 6 are detail views of one of the carbide- 35 cartridges and the mechanism for releasing said cartridges.

The generator 1 and gasometer 2 are supported on a base 3 side by side. The generator is closed on all sides except at the top, 40 where it is provided with a mouth 4, through which the cartridges are introduced. A clean-out 5 is provided in the lower portion of the generator, near where the latter is provided with the vertical side 6. Above the side 6 the

generator-body has the curved side 7, provided 50 with trough-like guides 8 on its interior, arranged side by side and adapted to guide the different cartridges as they submerge themselves by gravity when released. The numerals 9 designate partitions between the guides, 55 which maintain the cartridges in proper position after being submerged. There is a gas seal or apron 10 of zigzag shape in the upper portion of the generator, which is suitably disposed to permit the introduction of the cartridges and yet prevent the escape of any of the gas rising from the submerged carbide, said apron or seal extending from the top of the generator to a point below the water-line.

Rising from the top of the generator is a 65 frame 11, having vertical guide rods or wires arranged in pairs, as shown at 12, the number of pairs corresponding to the number of carbide-cartridges.

The numeral 13 designates a trip-shaft 70 journaled in brackets on the generator back of the frame 11, which shaft carries a ratchet-wheel 14 and trip-fingers 15, corresponding in number to the cartridges.

Independent mechanism is employed for 75 holding and releasing each cartridge. There is a barrel 16, having an open body 17, in the ends of which slides a bolt 18, having a trunnion 19.

The numeral 20 designates a shifting lever 80 pivoted to the barrel at 21 and having an arm which is provided with a slot which loosely receives the trunnion. The curved or bent end of the lever extends backwardly immediately over the corresponding finger 15 on 85 the trip-shaft, so that when the latter has been rotated sufficiently to bring the given trip-finger in engagement with said lever the bolt will be retracted, thus releasing the cartridge. Further rotation of the shaft will 90 cause the release of the next cartridge, and so on in succession.

The cartridges have a cylindrical body or shell 22, made in two detachable sections to permit introduction of the carbide, provided 95 with a conical lower end having an inlet-pipe 23. A convex perforated bottom 24 is positioned in the shell and supports the carbide

25. In the top of the shell is a puppet-valve 26, over which is a guard 27. The shell is provided with a bail 28, to which is connected a pull-rod 29, having a hooked upper end 30 5 and a cross-head 31. On one side the shell is provided with a perforated bolt-receiver 32, adapted to receive bolt 18, and on the other side is a lug 33, adapted to be engaged by a wire-retaining frame 34, hinged to apron or seal 10 at 35. This retainer rests on the lug 33 when the cartridge is in raised position, and when it has been submerged the retainer bears against the rod 29 and prevents the hook 30 from becoming detached from the lower 15 bar of frame 11. The rods 29 have their upper ends adapted to slide between the guide rods or wires 12 and are held in proper position by the contact of the cross-heads 31 with said guide-rods.

20. The numeral 36 designates the gas supply or inlet pipe leading from the gas-space of the generator to that of the gasometer and provided with a condensation-trap 37. The outlet or house pipe 38, leading from the gas- 25 ometer, has a condensation-trap 39. Disposed centrally within the gasometer 2 is a blow-off or safety pipe 40, one of whose ends is in the upper portion of the gasometer and the other end being disposed on the outside, where 30 it can discharge into the open air.

The numeral 41 designates the gas-bell, which is provided with rollers 42, adapted to travel on the side pieces of a vertical guide-frame 43, detachably secured to the gasometer at 44. A pipe 45, secured at its upper end to the top of the gas-bell, telescopes over blow-off pipe 40 and prevents the gas from escaping except when the hole 46 is disposed above the water-line. When the gas-bell has 35 raised sufficiently to position the hole above the water-line, the pressure has become excessive, and provision is thus made to relieve it. The gas-bell is provided with a pivoted or hinged pawl 47, suitably hung to engage 40 with the ratchet-wheel 14 when the bell has dropped from lack of suitable gas-pressure to 45 its lower limit, or nearly so.

The generator and gasometer having been filled with water and the parts properly arranged, the operation is as follows: The first cartridge released slides down the curved portion of the generator-shell until the abrupt side 6 is reached, whereupon it assumes a vertical position and is held by the engagement 50 of the hook 30 with the lower cross-bar of the frame 11. The water having access to the carbid, the gas generated raises the puppet-valve 26 and escapes upwardly through the water and into the gas-space, from which it 55 passes into the gasometer and raises the gas-bell. When the pressure has become sufficiently diminished in the gasometer, the bell drops, whereupon the pawl 47 engages and turns the ratchet-wheel. This action causes 60 the second trip-finger of the series to engage the lever of the second set of catch mechan-

ism and to retract the bolt from the cartridge, thus releasing the second cartridge, which slides down into the generator and assumes a position beside the first cartridge. The operation is repeated as the carbid in the cartridge being used loses its gas-generating properties until all the cartridges have been used, whereupon they have to be renewed.

Having thus described my invention, what I claim as new, and desire to secure by Letters Patent, is—

1. In an acetylene-generator, a tank having a mouth for the introduction of the carbid and an inclined side divided into a plurality of chutes or guideways, located adjacent the mouth and adapted to receive the carbid.

2. In an acetylene-gas generator, a tank having a mouth for the introduction of the carbid-cartridge and a side having an inclined portion leading from the mouth or adjacent thereto and terminating in an abrupt shoulder or upright portion in the lower part of the tank, said shoulder being separated from the side thereof to leave a space for the reception of the cartridges after gravitating down the inclined portion, a plurality of carbid-cartridges releasably held outside the mouth in position to gravitate down the inclined portion and means for holding them in upright position against the shoulder after gravitating down the inclined side and leaving the same.

3. In an acetylene-generator, the combination with a plurality of independent carbid-cartridges, of independent retaining mechanism for each cartridge consisting of a sliding catch-bolt and pivoted lever for operating the bolt, a shaft carrying a plurality of fingers corresponding to the levers and arranged to trip them in succession, and means for turning said shaft.

4. In an acetylene-generator, the combination with a carbid-cartridge, of mechanism for holding it in position consisting of a barrel, a bolt slidable in the barrel and provided with a trunnion, a lever pivoted to the barrel and having an arm loosely connected to the trunnion, a gasometer having a movable bell, a pawl connected to the bell, and a trip-finger, adapted for actuation by the pawl, which engages and moves the lever to release the cartridge.

5. In an acetylene-gas generator, the combination with a tank, of a frame having a plurality of guides, a plurality of carbid-cartridges having rods which slide in the respective guides and are provided with cross-heads bearing on the guides and with hooks for engaging the frame when the cartridges have been released, independent catch mechanisms for the respective cartridges, and means for releasing said catch mechanisms in succession at predetermined intervals.

6. In an acetylene-gas generator, the combination with a tank of a carbid-cartridge and

means for holding it in suspended position outside the tank, and an independent retaining device bearing against the cartridge.

7. In an acetylene-gas generator, the combination with a tank, of a carbid-cartridge and means for holding it in position outside the tank, and an independent hinged frame bearing against the cartridge and retaining it in proper position for submersion in the tank.
8. In an acetylene-gas generator, the combination with a tank, of a carbid-cartridge, a rod connected thereto and suitably guided,

means for holding the cartridge in position for submersion in the tank, and a retaining-frame on the tank which bears against the cartridge when the latter is raised and bears against the rod when the cartridge is lowered. 15

In testimony whereof I affix my signature in presence of two witnesses.

WILLIAM EDWARD SCOFIELD.
